UNITED STATES PATENT OFFICE.

JOSEPH C. HARVEY, OF CHICAGO, ILLINOIS, ASSIGNOR TO JOHN T. UNDERWOOD, OF BROOKLYN, NEW YORK.

TYPE-WRITING MACHINE.

1,152,944.

Specification of Letters Patent. Patented Sept. 7, 1915.

Application filed March 8, 1913. Serial No. 752,887.

To all whom it may concern:

Be it known that I, JOSEPH C. HARVEY, a citizen of the United States, residing in Chicago, in the county of Cook and State of Illinois, have invented certain new and useful improvements in Type-Writing Machines, of which the following is a specification.

This invention relates to means for locating two or more sheets in a typewriting machine, and making duplicate typewritten impressions thereon, and is particularly useful in bookkeeping operations, where an entry is made simultaneously on a ledger sheet and a statement; and it is also useful in billing operations and the like, as for instance where it is desired to make upon a journal or other record sheet duplicates of the individual entries made upon a number of bills, statements or other individual sheets.

According to one feature of my invention, the individual ledger or other record sheet is assembled in the machine with an interleaving ink strip, which may be of the same material as an ordinary inking ribbon, but which is retained mechanically in the machine for repeated use, thus avoiding the necessity of using carbon sheets and also gaining the advantage of making a permanent or record copy. A further advantage is gained in connection with this inking strip, inasmuch as it is made to disappear after the entries are typewritten, so that when the statement is withdrawn, the operator can inspect the entry made on the record sheet which is retained in the machine, and may correct the same or re-adjust the sheet, or, in the case of condensed billing, may advance the sheet to give the required space between successive entries on the record sheet. This ink strip is preferably formed upon the forward border of a web, which at its rear end is connected by a spring device to the typewriter, for the purpose of returning the ink strip to normal position, or causing it to disappear. The sheets and strip are all fed forwardly by the usual feed roll running upon the platen; and when said feed roll is released and the statement is withdrawn, the strip is automatically returned by means of said spring.

According to another feature of the invention, one of the work sheets, usually the ledger sheet, is laid upon a special work table which is arranged behind the platen in front of the usual paper shelf, and a pres-

sure roll carried by this work table at its lower end serves to press the work sheet against the platen. This work table has gages at its sides forming a sort of chute down which the work sheet may be guided; and the construction is such that if the work sheet is skewed a little when dropped upon the work table, it will right itself and feed squarely around the platen.

Other features and advantages will hereinafter appear.

In the accompanying drawings, in which the improvements are shown in connection with an Underwood front strike writing machine, Figure 1 is a view of an ink strip formed by inking the forward edge of the web of cloth; although other material may be employed in some cases. Fig. 2 is a perspective view of my improvements applied to the platen and platen frame of an Underwood writing machine. Fig. 3 is a sectional side elevation of the same, showing type impressions as being made upon the work sheets. Fig. 4 is a view similar to Fig. 3, but showing the parts in normal positions before any work sheet is inserted. Fig. 5 is a rear view of the auxiliary work table, showing the ink strip web as having been drawn down as the work sheets have been fed up around the front of the platen. Fig. 6 is a diagram to illustrate two rolls for advancing the record sheet to the platen and feed it around the same; both the special feed rolls being out of contact with the platen. Fig. 7 is a diagram to illustrate the method of introducing the ledger or other record sheet into the machine; the leading edge of the sheet being shown as resting upon the crown of the special feed roll. Fig. 8 is a diagram to illustrate the manner in which the record sheet is fed around by revolving the platen until its front edge emerges above the front scale. Fig. 9 is a view like Fig. 3, but showing the written statement as being partly in the machine. Fig. 10 is a diagram to show the sheets with the intervening ink strip as having been advanced by rotating the platen, to bring them to position to begin the first line of writing. Fig. 11 is a diagram to show the introduction of the individual sheet after the record sheet has been introduced.

The cylindrical platen 1 is mounted by its axle 2 in the ends 3, 4 of a platen frame, which are connected by a paper shelf 5, extending downwardly and forwardly to the

platens upon the introductory side thereof. Rods 6 and 7 also rigidly connect the platen frame ends. A guiding apron 8 usually curves forwardly from the lower end of the 5 paper shelf 5 around the under side of the platen and up in front thereof. A vibrating ribbon 9 is arranged as usual in front of the platen; and types 10 strike through said ribbon 9 against the platen or the paper 10 thereon.

The record work-sheet 11, which, in billing operations, is to remain in the machine and receive all the typewritten items which appear upon the bills, statements or individual work-sheets, is laid upon a supplemental work table or shelf 12, which may incline downwardly and forwardly with its lower end near the platen 1. This sheet is carried around under the platen and up in front 20 thereof, and adjusted in respect to the printing line by means of the usual scales 13.

The bill, statement or other individual work-sheet 14 is laid upon the paper shelf 5, and guided around the platen and adjusted to the scales 13. The usual roll 15 on the under side of the platen is used to feed the sheets forwardly after they are inserted; but is cast off while they are being introduced.

Between the record or general work-sheet 11 and the individual sheet 14, lies an inking strip 16, which enables the type to make impressions on the under sheet 11 corresponding to the typed impressions on the 35 outer sheet 14. This inking strip normally occupies the position seen at Fig. 2, with its advance edge flush with or below the edges of the scales 13, so as not to interfere with the adjustment of the work-sheets 11 40 and 14 to said scales.

The length of the inking strip is equal to or greater than the length of the line of writing upon the work-sheets. This inking strip remains in the machine, being adapted 45 to feed up with the work-sheets as the latter are written line by line, and then returning to the normal Fig. 2 position, thus disclosing the writing on the record sheet 11, and also permitting the latter to be re- 50 adjusted if required.

The inking strip 16 is flexible, and is connected by a flexible web 17 to a returning device, which may be in the form of a lever 18, pivoted at 19 upon the rear side 55 of table 12, and having a spring 20 which tends constantly to return the flexible web 17 and its ink strip 16 to normal position. The lever 18 is connected by a link 21 to a metallic binding strip 22 provided upon the flexible web 17, and preferably extending for some distance along the opposite edges thereof, as at 23. The normal position of the ink strip is determined by stops 24, against which the binding strip 22 is held 60 by means of the spring 20, Fig. 2.

The record sheet 11 is first inserted in the machine, Fig. 7, with its bottom edge resting upon the auxiliary roll or rolls 25, which are mounted by means of an axle 26 in ears 27 pendent from the sides of auxiliary work table 12. The sides of said table are bent up to form opposite gages 28, and these are preferably spaced so that the work-sheet 11 fits loosely between them, so as to be gaged by one or both thereof. The leading edge of a sheet catches momentarily upon the crown of roll 25, but the lower edge of the auxiliary table 12 is bent forwardly at 29, Fig. 4, to prevent the sheet catching too far back on roll 25 to form a deflector. By rotating the platen by means of the usual knob 30, the sheet 11 is led or dropped between the roll 25 and the platen. 75

It will be understood that the advance edge of the work sheet 11 may be gaged or straightened by resting upon roll 25, but if said sheet should be a little askew at that time, it will be found to right itself while it is dropping off the roll and into the bight of the roll 15 and the platen 1; so that the side edges of the sheet will be parallel with the side gages 28. The sheet is pressed by said roll against the platen and fed forwardly down around and up in front of the platen, Fig. 8, between the latter and the 90 inking strip 16. During this operation, roll 15 running upon the under side of the platen, is cast off. 95

Preferably the necessary pressure of the feed roll 25 against the platen is effected by 100 the weight of the auxiliary table 12, which may have at its sides hooks 31 to pivot upon the rods 6; the weight of the shelf with its appurtenances being back of the pivot rod 6, thus causing the roll 25 (which 105 is beneath said rod) to swing forwardly against the platen. To release roll 25, it is only necessary to swing shelf 12 forwardly. It is noted that the hooks 31 permit the shelf 12 to be readily detached from the machine when it is desired to use the same for other work. 110

When the operator has advanced the sheet 11 far enough, he may adjust it to the printing line by means of scales 13; the inking 115 strip 16 not hindering this operation, as it does not at this time project above said scales 13, Fig. 8. The operator then inserts the individual work-sheet 14, Fig. 11, the same passing freely down around under the platen and up in front thereof (the roll 15 being still cast off), and adjusts the sheet to the scales 13. The operator then lifts the key 31^a, and restores the roll 15. He then advances the platen the distance of one or more line-spaces, either by means of the knob 30 or by means of the usual line-space mechanism which includes the line-space wheel 32. The roll 15 advances both sheets 11 and 14, together with the intervening ink 120 125 130

strip 16, so that they will all project above the scales 13, Fig. 10. The record sheet 11 may project farther than the other two. The operator then writes the line by means 5 of the usual types 10, Fig. 3, and in some cases, he may write several lines, advancing the platen by means of said line-space mechanism, together with said work-sheets 11 and 14, and ink strip 16; the spring 20 yielding 10 to permit the ink strip 16 to be advanced in this manner. It will be understood that the roll 15 is effective to feed the strip 16 as well as the sheets. Having completed the entry upon the statement, the operator 15 presses the key 31^a to cast off the roll 15, and then draws the individual sheet 14 forwardly to remove it from the machine. The tension of spring 20 is very light, so that the upward pressure of the usual yielding apron 20 8, under the platen, is sufficient to detain the flexible web 17 while said sheet 14 is being drawn out, (Fig. 9,) until the latter is nearly or quite withdrawn from the platen. This releases web 17, and the spring 20 returns 25 the latter and strip 16 to normal Fig. 2 position. The record sheet 11, of course, is not disturbed while the individual sheet 14 is being withdrawn, nor while the ink strip 16 is retracted. The operator now inserts a 30 fresh sheet 14 and adjusts it to the printing line as before.

The usual feed rolls which usually run upon the under front side of the platen of the Underwood machine, are omitted, so 35 that there is no liability of ink being thereby set off from the strip 16 onto the face of the record sheet 11. The distance between the printing line and the feed roll 15 is so great as to permit of an ample area of inking strip for the purpose of writing a short statement or entry, which often consists of only a single line of typewriting.

The ink strip 16 may be formed by inking the forward portion of the flexible web 17, 40 which may consist of cloth similar to that of which typewriter ink ribbons are made. The cloth needs to be inked only on one side; and the other side thereof may have an impermeable coating 33, as indicated at 45 Fig. 1, so as not to offset on the rear face of the front work-sheet 14.

It will be understood that the retraction or disappearance of the ink strip 16 exposes the type impressions on the sheet 11, 50 so that the operator can examine the same and correct them if necessary, and may also advance the sheet by turning the knob 30 so as to leave any required amount of space between successive entries on the record sheet 11; or he may further adjust said sheet 60 to bring any desired ruled line thereon to register with the scales 13.

Having adjusted the fresh sheet 14, the operator restores the feed roll 15, and proceeds to typewrite the new entry, which is

of course written in the desired place upon the new sheet, and also appears in proper location beneath the previous entry on the record sheet 11. Thus the insertion and withdrawal of the sheets 14 proceeds until 70 the sheet 11 is filled; whereupon a fresh record sheet 11 is inserted, and the operation continues.

Instead of having the roll 25 run upon the platen, it may coöperate with another 75 roll 34, Fig. 6, to feed the sheets 11 to the platen and forwardly around the same while the latter remains stationary, the roll 25 being provided for this purpose with a finger-wheel 35. These rolls 25 and 34 may rotate 80 idly when sheet 11 is being drawn forward by the coöperation of the platen 1 with the bottom roll 15.

While the improvements have been described in connection with the operation of 85 condensed billing, it will be understood that a use of the machine which is of equal or greater value, is its use for bookkeeping purposes. In this connection the record sheet is usually a loose leaf of a ledger; and 90 the individual sheet is a statement of account. In using the invention for this purpose, the operator, after withdrawing the individual sheet, also withdraws the record sheet 11, since the latter bears at its top the name of a single customer, and only that customer's items are entered thereon. After 95 the various items are entered on the several statements and ledger leaves, both statements and leaves are properly filed, and when the next transaction occurs with any customer, his statement and ledger leaf are selected and the item entered thereon, whereupon they are re-filed in their original places. Thus the ledger sheet constantly shows the 100 condition of the customer's account, while the statement is added to day by day, so that at the end of the month it is all ready for mailing without further labor.

One of the great advantages of the present invention is that it facilitates the introduction of the ledger sheet and the adjustment thereof to the printing line without being obscured by a carbon or other inking device, such as usually covers the face of the record sheet in condensed billing and other operations. The operator may not only easily see the last line of writing on the ledger sheet, but may quickly adjust the 110 same to the printing line by means of the usual front scales 13. Thus it will be seen that the sheets may be easily inserted independently of each other and each properly adjusted to the printing line independently 115 of the position occupied by the other, while each may be quickly withdrawn when the roll 15 is cast off; and thus the operation of 120 bookkeeping is greatly simplified and facilitated, particularly where the amounts are 125 added by means of a computing attachment 130

on the typewriting machine, for which my invention is especially adapted.

It will, of course, be understood that it is a matter of option, especially in bookkeeping, whether the sheet 11 shall be the record sheet or the individual sheet. Of course, the type impressions on the inner sheet 11 are not quite so clear as those on the outer sheet; and it is therefore optional whether 10 the statement or the ledger sheet shall receive the clearer impressions.

Variations may be resorted to within the scope of the invention, and portions of the improvements may be used without others.

15 Having thus described my invention, I claim:

1. The combination, with a revoluble platen, and a platen frame having a paper shelf at the rear of the platen; of an auxiliary work shelf between the platen and the first-named shelf hinged to said platen frame to permit its lower end to swing toward said platen; and a roll carried by the auxiliary shelf at its said lower end to be 25 pressed by the weight of said shelf against said platen for coöperation with the latter to feed forwardly sheets which are laid upon said auxiliary shelf.

2. The combination, with a revoluble 30 platen, and a platen frame having a paper shelf at the rear of the platen; of an auxiliary work shelf between the platen and the first-named shelf having a detachable hinged mounting to permit its lower end to swing 35 toward said platen; and a roll carried by the auxiliary shelf at its said lower end to be pressed by the weight of said shelf against said platen for coöperation with the latter to feed forwardly sheets which are laid 40 upon said auxiliary shelf.

3. The combination, with a revoluble platen, a platen frame having a paper shelf at the rear of the platen, and a horizontal rod mounted longitudinally in said frame; of an auxiliary work shelf between the platen and the first-named shelf hinged upon 45 said rod to permit its lower end to swing toward said platen; and a roll carried by the auxiliary shelf at its said lower end to be 50 pressed by the weight of said shelf against said platen for coöperation with the latter to feed forwardly sheets which are laid upon said auxiliary shelf.

4. The combination, with a revoluble 55 platen, a platen frame having a paper shelf at the rear of the platen, and a horizontal rod mounted longitudinally in said frame; of an auxiliary work shelf between the platen and the first-named shelf having a 60 pair of opposite hooks thereon detachably and pivotally engaging said rod, to permit the lower end of said auxiliary shelf to swing toward said platen; and a roll carried by the auxiliary shelf at its said lower end 65 to be pressed by the weight of said shelf

against said platen for coöperation with the latter to feed forwardly sheets which are laid upon said auxiliary shelf.

5. The combination with a revoluble platen and a platen frame, of an auxiliary 70 work shelf, an inking strip extending along the platen and means yieldingly connecting said strip to said auxiliary work shelf to permit the strip to be fed around the platen together with a work sheet supplied from 75 said auxiliary work shelf.

6. The combination with a revoluble platen and a platen frame, of an auxiliary 80 work shelf, an inking strip extending along the platen, and a flexible web at the forward end of which said strip is arranged, said web having at its rear end a connection to said work shelf.

7. The combination with a revoluble platen and a platen frame, of an auxiliary 85 work shelf, an inking strip extending along the platen, a flexible web at the forward end of which said strip is arranged, said web having at its rear end a connection to said work shelf, and a spring to return the strip and web to normal position after being fed around the platen.

8. The combination with a revoluble platen and a platen frame, of an auxiliary 95 work shelf, and an inking strip for coaction with a work-sheet from said auxiliary work shelf, connected with the latter and extending along the platen, said strip in normal position lying below the printing line on the platen so as to disclose the writing.

9. The combination with a revoluble platen and a platen frame, of an auxiliary work shelf, an inking strip extending along the platen, and means yieldingly connecting said strip to said work shelf to permit the strip to be fed around the platen together with a work sheet from said auxiliary work shelf, said strip in normal position lying below the printing line on the platen so as to disclose the writing.

10. The combination with a revoluble platen, a platen frame, and a scale for the front of the platen, of an auxiliary work shelf, and an inking strip connected to said auxiliary work shelf and normally lying between the scale and the platen.

11. The combination with a revoluble platen, a platen frame, and a scale for the front of the platen, of an auxiliary work shelf, and an inking strip connected to said auxiliary work shelf and normally lying between the scale and the platen, but sufficiently below the printing line to enable said scale to be used for adjusting a work sheet from said auxiliary work shelf inserted between the inking strip and the platen.

12. The combination with a revoluble platen, a platen frame, and a scale for the front of the platen, of an auxiliary work shelf, an inking strip connected to said aux-

- iliary work shelf and normally lying between the scale and the platen, but sufficiently below the printing line to enable said scale to be used for adjusting a work sheet from said auxiliary work shelf inserted between the inking strip and the platen, releasable means for feeding the work sheet and ink ribbon around the platen, and means for retracting the strip or causing it to disappear.
13. The combination with a revolute platen and a ribbon in front thereof through which the types may strike against the platen, of an auxiliary work shelf, and an inking strip between said ribbon and the platen, said strip connected to said auxiliary work shelf at the introductory side of the platen in a manner to permit a work sheet from said auxiliary work shelf to be introduced between the platen and the strip, and also to permit another work sheet to be inserted around the platen between the strip and the ink ribbon.
14. The combination with a revolute platen and a ribbon in front thereof through which the types may strike against the platen, of an auxiliary work shelf, an inking strip normally disposed between said ribbon and the platen for coaction with a work-sheet from said auxiliary work shelf inserted between said inking strip and said platen, a scale in front of said inking strip for adjusting said work-sheet, releasable means to feed said work-sheet and inking strip, and means to return the strip to normal position upon the release of said feeding means, said strip mounted in a manner to permit another work-sheet to be inserted around the platen between the strip and ink ribbon.
15. The combination with a revolute platen, a platen frame, and a scale for the front of the platen, of an inking strip normally lying between the scale and the platen, a feed roll bearing upon the under side of the platen, said strip occupying a position on the platen between said roll and said scale, and a web joined to said strip in front of said roll, whereby pressure of the strip by the roll against the work-sheet is avoided.
16. The combination, with a revolute platen, and a platen frame having means to guide the work to the platen; of an auxiliary work-support or guide, an inking-sheet-carrying bar mounted for movement toward and away from said platen, to which bar the inking sheet is attached to be shifted thereby; a roll co-operative with said platen to feed the work with the inking strip around the platen, said feed roll and platen constituting companion elements, one of which is releasable with relation to the other; and means for moving said sheet-carrying bar away from the platen when said releasable element is so released.
17. The combination, with a platen; of an inking strip extending along the platen; a work shelf leading toward said platen; releasable means in rear of said inking strip for feeding together, around said platen, the said strip and a work-sheet from said shelf; a flexible web in rear of said feeding means and connected to said strip to feed therewith; and means associated with said web for automatically returning the same and said strip to normal position upon the release of said feeding means.
18. The combination, with a platen; of an inking strip extending along the platen; a work-shelf leading toward said platen; releasable means for feeding together, around said platen, the said strip and a work-sheet from said shelf; a flexible web connected to said strip to be fed therewith; a lever connected to said web and movable thereby during the operation of said feeding means; and a spring connected to automatically return said lever, and with it said web and said strip, upon the release of said feeding means.
19. The combination, with a platen; of an inking strip extending along the platen; a work-shelf leading toward said platen; releasable means for feeding together, around said platen, the said strip and a work-sheet from said shelf; a flexible web connected to said strip to be fed therewith, said web having a metallic binding at its upper edge; and spring means connected to said binding for automatically returning said web and said strip upon the release of said feeding means.
20. The combination, with a platen, and a platen frame having a paper shelf associated with it and leading toward said platen; of an inking strip extending over a limited portion only of the circumference of the platen; and a non-inking web extending longitudinally along the shelf and beyond the lower end thereof, and connected at opposite ends to said shelf and said inking strip.
21. The combination, with a platen, and a platen frame having a paper shelf associated with it and leading toward said platen; of an inking strip co-extensive longitudinally with the printing field on the platen and extending over a limited portion only of the circumference of said platen; and a non-inking web extending longitudinally along the shelf and beyond the lower end thereof, and connected at opposite ends to said shelf and said inking strip.
22. The combination, with a platen, and a platen frame having a paper shelf associated with it and leading toward said platen; of an inking strip extending over a limited portion only of the circumference of the platen; a non-inking web extending longitudinally along the shelf and beyond the lower end thereof, and connected at its lower end to said strip; and a yielding connection between the upper end of said web and said

shelf, to permit said strip to be fed, together with a sheet from said shelf, over the printing field on said platen.

23. The combination, with a platen, and a platen frame having a paper shelf associated with it and leading toward said platen; of an inking strip extending over a limited portion only of the circumference of the platen; a non-inking web extending longitudinally of said shelf and beyond the lower end thereof, and connected at its lower end to said strip; and a yielding connection between the upper end of said web and said shelf, to permit said strip to be fed, together with a sheet from said shelf, over the printing field on said platen, and to automatically retract said strip upon the completion of the feeding operation.
- 15 24. The combination, with a platen, and

a platen frame having a paper-shelf associated with it and leading toward said platen; of an inking strip extending over a limited portion of the circumference of the platen; a non-inking web extending longitudinally along said shelf and below the lower end thereof, and connected at its lower end to said strip; and a connecting spring between the upper end of said web and said shelf, to permit said strip to be fed, together with a sheet from said shelf, over the printing field on said platen, and to automatically retract said strip upon the completion of the feeding operation. 20 25 30
